UNITED STATES PATENT OFFICE.

JOHN T. TRUMBLE, OF SAGINAW, MICHIGAN, ASSIGNOR OF ONE-HALF TO CHARLES C. SPREEN, OF SAGINAW, MICHIGAN.

AUTOMOBILE-BODY.

1,124,676.

Specification of Letters Patent. Patented Jan. 12, 1915.

Application filed April 29, 1912. Serial No. 693,915.

To all whom it may concern:

Be it known that I, JOHN T. TRUMBLE, a citizen of the United States of America, residing at Saginaw, in the county of Saginaw and State of Michigan, have invented certain new and useful Improvements in Automobile-Bodies, of which the following is a specification, reference being had therein to the accompanying drawings.

10 In automobiles as usually constructed, the electric wiring for lighting and other purposes is liable to become loosened and broken by the constant vibration of the vehicle and short circuits caused by the insulation of 15 the wires becoming worn away or soaked with water or oil. The services of an expert are required to properly repair or install such wiring and much time is consumed in stringing and securing the wires 20 in place.

The object of this invention is to provide a body construction which is such that the wires will be inclosed, held and protected, thus obviating all liability of breakage and 25 short circuits, and the work of wiring is greatly simplified and lessened.

To this end the invention consists in the matters hereinafter set forth and more particularly pointed out in the appended claim, 30 reference being had to the accompanying drawings, in which—

Figure 1 is a longitudinal section through an automobile body having a construction embodying the invention; Fig. 2 is a sectional detail of a body sill, taken on the line $x-x$ of Fig. 1; Fig. 3 is a front elevation of a dash-board; Fig. 4 is a section on the line $y-y$ of Fig. 3; Fig. 5 is an enlarged sectional detail of a hood rail; Fig. 6 is a detail similar to that of Fig. 5 showing a modified construction, the same being a section on line VI of Fig. 8; Fig. 7 is a section of a sill on the line VII of Fig. 8 showing a modified construction; and Fig. 8 is a detail 45 tail showing a vertical section through a portion of the dash and the adjacent parts of the body sill and hood rail in elevation with parts broken away to show the construction.

50 As an illustration of the application of this invention, an automobile body is shown provided with wiring for electric lights, but it will be understood that the invention applies as well to the wiring of automobile bodies for other purposes.

An automobile body of any desired form and construction is provided with longitudinal side sills 10 which are each formed with a longitudinal groove 11 to receive insulated electric wires 12 leading from a storage battery indicated at 13 (Fig. 1) and located beneath the rear seat of the body. When the body is being constructed these wires 12 are laid in the groove to receive them and a strip 14 of fabric, preferably adhesive tape, is placed over the groove and wires. A wooden covering strip 15 is then secured by means of screws 16 or other suitable fastening devices, over the strip 14 to hold it in place and effectually close the side of the groove 11. At the forward end of the sills 10, certain of the wires 12 are carried upward in suitable grooves 17 formed in the face of the dash-board 18 and these grooves are likewise covered by fabric 75 strips 19 similar to the strips 14 and by a thin board 20 or wood strips similar to the strips 15. These wires are carried upward on the dash to a suitable switch or other controlling device 21. Some of the wires 80 12 which extend forwardly along the side sills 10 are carried forward at each side of the hood 22 within a groove 23 in the hood rail 24 which is secured in place in the usual manner upon the upper side of the side 85 members 25 of the channel iron chassis frame. These forwardly extending wires are thoroughly protected and held in their grooves 23 in the same manner that they are held in the sills 10, that is, a fabric 90 strip 26 is placed over the groove which is in the lower side of the rail and a wood strip 27 secured to said lower side of the rail over the groove by means of screws or other fastening means. These wires are 95 thus carried forward to supply electric current for the lamps which are commonly supported at the forward end of the chassis.

In the construction shown in Fig. 6, the hood rail 28 is shown provided with a separate groove 29 for each wire and the wooden strip 30 for closing these grooves is set into a groove or channel formed in the face of the rail. Likewise in the modified construction of the sill shown in Fig. 7 a separate groove 31 is provided for each wire and the closing strip 32 is set into a channel formed in the inner face of the sill.

By providing the automobile body with grooves when its parts are machined up in 110

the manufacture of the body, the electric wiring may be laid into these grooves before the body is placed upon the chassis thus greatly facilitating the work of wiring and 5 when the wires are so laid and secured in place by the fabric covering and wooden strip, they are securely held against all possibility of becoming broken or their insulation chafed and worn through by the vibration 10 of the machine. Water and oil is also positively excluded from the groove so that short circuits cannot be caused by the insulation of the wires becoming soaked with oil or other fluid. It will seldom be necessary 15 to disturb the wiring when secured in place in this manner, as when the body is removed for the purpose of repairing the automobile the wiring will remain in place upon the body and it will, therefore, always be 20 in a position to be connected up when the body is again secured in place upon the chassis.

Obviously changes may be made in the details of construction without departing 25 from the spirit of my invention and I do not therefore wish to limit myself to the particular form and arrangement shown.

Having thus fully described my invention what I claim is:—

Copies of this patent may be obtained for five cents each, by addressing the "Commissioner of Patents, Washington, D. C."

In an automobile body, side sills having 30 the confronting sides thereof provided with longitudinal grooves arranged in parallelism and extending from one end of each sill to the opposite end thereof, a dash board supported by the forward ends of said sills 35 and having the front side thereof provided with vertical grooves having the upper ends thereof converging to a point centrally of said dash board, said dash board having openings formed therein at 40 the lower ends of the vertical grooves thereof, wires arranged in the grooves of said sills and extending from said grooves through the openings of said dash board into the grooves thereof, strips countersunk 45 in the inner sides of said sills and closing the grooves thereof, and a board secured to said dash board and closing the grooves thereof, said board coöoperating with said strips in preventing said wires from becoming accidentally displaced.

In testimony whereof I affix my signature in presence of two witnesses.

JOHN T. TRUMBLE.
